UNITED STATES PATENT OFFICE.

WILLIAM BERSSENBRUGGE, OF MILWAUKEE, WISCONSIN.

MACHINE FOR APPLYING CORNER IRONS.

Application filed March 22, 1928. Serial No. 263,808.

This invention relates to a machine for applying corner irons.

In certain articles of furniture, for example, card tables, it is the usual practice to provide some form of corner iron. These irons have been attached in various ways in order to protect the corners, but it has been found that the usual modes of attaching them are relatively slow, and this invention is designed to provide a novel form of machine which is adapted to quickly and securely attach the corner iron in a novel manner.

Further objects are to provide a machine which is so constructed that a single movement of the operator draws the table or other article into position and thereafter clinches and locks the corner iron to the corner of the table.

Further objects are to provide a machine which is so constructed that it has the minimum number of parts, and in which the utmost simplicity and ruggedness are obtained.

An embodiment of the invention is shown in the accompanying drawings in which:

Figure 1 is a plan view of the machine showing the table in place with parts broken away;

Figure 2 is a sectional view on the line 30 2-2 of Figure 1;

Figure 3 is a sectional view on the line 3-3 of Figure 2;

Figure 4 is a sectional view on the line 4-4 of Figure 2;

Figure 5 is a view of the dies looking from the inner side of the machine, a part of the figure being in section;

Figure 6 is a plan view of the end of the table with the dies in their operative position;

Figure 7 is a sectional view on the line 7-7 of Figure 6;

Figure 8 is a view corresponding to Figure 7 showing the dies open before the closing stroke;

Figure 9 is a sectional view on the line 9-9 of Figure 5;

Figure 10 is a view from the underside of one of the corners of the table;

Figure 11 is a side elevation of the corner iron.

Referring to the drawings, it will be seen that the machine comprises a pair of guides 1 which are supported by vertical uprights 2 and carry at their ends transverse mem-

bers 3. The vertical uprights also carry at their lower ends longitudinal and transverse members 4 and 5. All of these parts are preferably formed of channel shape and thus provide the maximum strength for the minimum weight.

The guides 1 carry a table supporting slide 6 (see Figure 4) which is shouldered and rides upon the guides 1. Clips 7' are bolted to the slide 6 to retain it against moving upwardly from the guides 1. The guide 6 carries a turn table or rotary disc 8 which, in turn, is provided with a plurality of radiating arms 9. These arms are provided with upstanding ears or fingers 10 which engage opposite sides of the table adjacent the corners, as shown most clearly in Figures 1 and 2. The fingers 10 are also spaced from the extreme corners of the table to allow room for the corner irons hereinafter described.

As shown in Figure 2, the slide 6 is provided with an apertured lug 7 through which a rod 11 slidably passes. This rod is provided with an adjusting nut 12 at its outer end and a relatively stiff spring 13 is interposed between the nut and the lug 7. Relatively lighter springs 14 are connected to the slide 6 and to the rear of the frame of the machine, as shown in Figures 1 and 2, so that when the pressure of the spring 13 is released, the guide 6 moves towards the rear of the machine. The forward end of the rod 11 is connected to a lever 15 carried by a rock shaft 16. The rock shaft 16 is further provided with a lever 17 connected by means of a rod 18 with a foot pedal 19 provided with a foot receiving portion 20 preferably located outside the outline of the frame of the machine, as shown in Figure 1. Thus, when the operator places his foot upon the treddle or foot lever 19, the table is moved forwardly, that is to say, to the right, as viewed in Figures 1 and 2.

The machine is provided with a bracket 21 adjacent its forward end which carries the stationary die 22, and one or more guiding rods 23. Upon the guiding rods 23, the movable die 24 is slidably carried. This movable die is connected by means of a rod 25 with the foot pedal or foot lever 19, as shown in Figures 2 and 3. It is to be noted that the rods 18 and 25 are connected to the foot lever 19 on opposite sides of its fulcrum 26, so that when the rod 18 moves downwardly

upon operation of the lever, the rod 25 moves upwardly and thus forces the movable die towards the stationary die.

It is to be noted that the rod 25 is threaded into the movable die 24 to secure the requisite adjustment, and a lock nut 27 (see Figure 2) is employed to lock the rod 25 to the movable die 24.

It is to be noted particularly from Figures 6 to 9, that the stationary die 22 and the movable die 24 are each provided with lips indicated respectively by the reference characters 28 and 29. These lips are arranged in pairs for each die and the parts of each pair are at right angles, as shown particularly in Figure 6. The movable die 24 is provided with a cylindrical hollow portion 30 (see Figure 5) within which a headed plunger 31 is slidably positioned. This plunger is urged upwardly by means of the spring 32, the lower end of the spring bearing against a plug 33 screwed into the lower end of the cylindrical member. The bottom head of the plunger 31 limits its upward motion.

Although this invention is applicable to a large variety of uses, it is eminently suited to the placing of corner irons upon the corners of card tables or similar devices. These card tables are regularly provided with light wood frame members 34 which have a groove 35 in their upper edges. These frame members receive the cardboard top 36 and such cardboard top is usually covered by means of a fabric or other sheath 37 whose edges are tucked into the slot 35.

The corner irons which this machine applies are formed of a vertical channel section 38 (see Figure 11) provided with arms 39 projecting at right angles to each other. The lower ends of the corner irons are provided with tongues 40.

The corner irons are formed with the upper arms or lips 39 curved or channel-shape. These upper arms are hooked over the corners of the table.

In using the machine, a table is placed, as indicated in Figures 1 and 2. A corner iron is positioned at the corner of the table with the upper channel members 39 fitting into the groove 35. Thereafter, the operator depresses the foot pedal or lever 19. This first forces the table forwardly, as the pressure of the spring 13 overcomes the lighter springs 14 (see Figure 2). This motion is very small and occurs before the movable die 24 has moved into proximity to the table. Continued motion of the lever 19 forces the movable die 24 upwardly and as it moves upwardly the spring pressed plunger 31 shoves the table up against the overhanging lip or jaw 28 of the stationary die 22, as shown in Figure 7. It is to be noted at this point that the lip 28 of the movable die is positioned above the normal plane of the

table when carried by the machine. As the operator continues the downwardly stroke of the foot pedal, the movable die continues upwardly until it arrives at the position shown in Figure 7. In this position, it will be seen that the movable die has guided the fingers or cleats 40 outwardly and upwardly around the bottom or outer corner of the frame member 34, and that the jaws 29 of the movable die have clinched these cleats or fingers, as shown in Figure 7.

Further, it will be noted, as is apparent from Figures 7 and 10, that the fingers are aided in their motion into the wood of the frame by the cutting action of the jaws 29 which actually cut a slight slit into the underside of the wood of the frames.

It will be seen that the cleats are very tightly forced into place and that the corner irons are tightly bound to the table without the use of any auxiliary fasteners whatsoever. After one corner has been finished, the operator rotates the table a quarter turn and goes through the same process.

In actual tests with the machine, it has been found that a very high speed may be maintained throughout a long period without fatigue on the part of the operator and with scarcely any thought on his part.

It will be seen that a very simple type of corner iron applying machine and a simple process of applying the corner irons has been provided by this invention.

It is to be distinctly understood that while the invention has been described as applicable to card tables particularly it is not to be so limited, as this mode of describing the invention was chosen to illustrate one of the articles of furniture which the machine will successfully handle.

It is to be distinctly understood that where the term "table" appears in either the specification or claims, it is to be given a broad meaning to cover any article of furniture or similar construction.

Although the invention has been described in considerable detail, such description is intended as illustrative rather than limiting as the invention may be variously embodied and as the scope of such invention is to be determined as claimed.

I claim:

1. A machine for applying corner irons to the corners of tables comprising a frame, a carriage for the table, a pair of dies having jaws projecting above and below the plane of the upper and lower edges of the table, means for moving the table to present a corner thereof between the dies, and means for moving the dies towards each other, the lower of said dies having its jaws curved to curve and clinch the lower portion of the corner iron into the table.

2. A machine for applying corner irons to the corners of tables comprising a frame for

carrying the table, a pair of normally spaced dies having jaws for overhanging and underhanging the upper and lower faces of the corner of the table, and means for moving the table towards the jaws and thereafter for causing the jaws to move towards each other to thereby clinch the corner iron in place by bending the lower portion thereof into binding engagement with the lower face 10 of the table.

3. A machine for applying corner irons to the corners of tables, such corner irons consisting of an upper overhanging lip and lower tongues, said machine comprising means for holding the table, a pair of dies positioned above and below the corner of the table, means for causing relative motion between the dies, the lower of said dies having curved jaws underhanging the lower edge 20 of the table and bending and forcing the said tongues into the table, and means connected with said first mentioned means for first moving the table into position to be engaged by said dies.

25 4. A machine for applying corner irons having a channelled upper edge and a plu-

rality of downwardly projecting portions, said machine comprising means for holding an article to which the irons are to be applied, means for moving said article into 30 the operative zone of said dies, means for causing the dies to approach each other, the lower of said dies having jaws curved and shaped to clinch the said tongues into the lower portion of the article of furniture, 35 both of said means being operated by a single operative member.

5. A machine for applying corner irons to card tables, said machine comprising a body portion, a slide carried by said body 40 portion and having a revoluble support for a table, a pair of dies carried by said body portion, means for moving said table towards said dies, and means for causing said dies to approach each other to clinch the 45 corner irons upon the corner of the table.

In testimony that I claim the foregoing I have hereunto set my hand at Milwaukee, in the county of Milwaukee and State of Wisconsin.

WILLIAM BERSSENBRUGGE.
